UNITED STATES PATENT OFFICE.

JAMES PRINGLE COCHRANE, OF EDINBURGH, SCOTLAND.

DESIGN FOR A GOLF-BALL.

50,883.

Specification for Design.

Patented June 5, 1917.

Application filed January 23, 1917. Serial No. 144,065. Term of patent 7 years.

To all whom it may concern:

Be it known that I, JAMES PRINGLE COCHRANE, a subject of the King of Great Britain and Ireland, and a resident of Edinburgh, Scotland, (whose postal address is Murano Works, Albert street, Edinburgh, Scotland,) have invented a new, original, and ornamental Design for Golf-Balls, of which the following is a specification, reference being had to the accompanying drawing, forming part thereof.

2 is a section of part of such golf ball showing my new design.

I claim:

The ornamental design for a golf ball, as shown.

In testimony whereof I have signed my name to this specification in the presence of two subscribing witnesses.

JAMES PRINGLE COCHRANE.

Witnesses:

ROBERT FRANCIS HUTCHISON,
BRIDGET ANN ROBERTSON.
